UNITED STATES PATENT OFFICE

147,122

DESIGN FOR AN ASH TRAY

Bruce N. Flickinger, Glendale, Calif.

Application November 30, 1945, Serial No. 124,229

Term of patent 3½ years

(Cl. D85—2)

To all whom it may concern:

Be it known that I, Bruce N. Flickinger, a citizen of the United States, residing in the city of Glendale, in the county of Los Angeles and State of California, have invented a new, original, and ornamental Design for an Ash Tray, of which the following is a specification, reference being had to the accompanying drawing, forming part thereof.

In the drawing:

I claim:

The ornamental design for an ash tray, as shown.

BRUCE N. FLICKINGER.
